UNITED STATES PATENT OFFICE.

WINFIELD S. COOK, OF BINGHAMTON, NEW YORK.

DESIGN FOR A LOCK-SPIKE.

49,704.

Specification for Design.

Patented Sept. 26, 1916.

Application filed May 10, 1915. Serial No. 27,273. Term of patent 7 years.

To all whom it may concern:

Be it known that I, WINFIELD S. COOK, a citizen of the United States, residing at Binghamton, in the county of Broome and State of New York, have invented a new, original, and ornamental Design for Lock-Spikes, of which the following is a specification, reference being had to the accompanying drawing, forming part thereof.

Figure 1 is a perspective view of the lock

spike, showing my new design, and Fig. 2 is a side elevation of the lock spike, showing my new design.

I claim:

The ornamental design for a lock spike, as shown.

WINFIELD S. COOK.

Witnesses:

E. H. MOODY,
E. C. MOODY.
